UNITED STATES PATENT OFFICE

GUSTAF DALÉN, OF STOCKHOLM, SWEDEN.

SAFETY DEVICE FOR INCANDESCENT-GAS-LIGHT BURNERS.

1,132,305.

Specification of Letters Patent. Patented Mar. 16, 1915.

Application filed October 26, 1911. Serial No. 656,894.

To all whom it may concern:

Be it known that I, GUSTAF DALÉN, a subject of Sweden, residing at Stockholm, Sweden, have invented new and useful Improvements in Safety Devices for Incandescent-Gas-Light Burners, of which the following is a specification.

The present invention refers to a safety device, to be used in connection with lighting plants, in which incandescent light burners are supplied with a mixture of gas and air under pressure, said mixture being established in a mixing apparatus, communicating with the burners.

15 The invention has for its object to avoid explosion of the mixture of gas and air in the conduit, caused by accidental flowing back of the flame from the burner to the gas mixture conduit, and consists in a safety device placed for this purpose in front of the incandescent gas burner.

The invention moreover has for its object to prevent explosion of the mixture of gas and air in the mixing apparatus in the event, that the above mentioned safety device should not work, and consists for this purpose in a safety device, placed after the mixing apparatus, in the direction of the flow of gas and air mixture to be reckoned.

30 On the drawing a mixing apparatus is shown in elevation in connection with a conduit between the same and an incandescent gas burner, said conduit and gas burner being provided with safety devices according to the invention. The drawing shows said latter parts in longitudinal section.

1 indicates a mixing apparatus of any suitable construction for mixing combustible gas and air in desired proportions.

40 2 is the gas supply pipe and 3 the air supply pipe of the mixing apparatus. In the conduit between said latter and the burner 8 a safety apparatus is inserted, which in the constructional form shown consists of a casing 4, provided with a partition wall 5, reaching almost to the bottom as in fluid seal devices. The casing 4 is partly filled with an easily fusible, finely divided metal 6 such as lead. The metal layer allows the necessary gas-air mixture to pass, the spaces between the metal pieces being so small as to prevent a flame burning in the conduit 7 to be transmitted through the casing 4. However if the gas in the casing should be 55 ignited, the metal 6 will fuse and form a

fluid seal, shutting off the mixing apparatus from the conduit 7.

The second safety device, which is inserted in front of the incandescent gas light burner 8 consists in the constructional form 60 shown of a screw bolt 10, screwed into the pipe section 9 of the gas conduit 7, and nearly filling up the gas channel 11 of the pipe section, only leaving a narrow annular opening for the passage of the gas. The 65 conical end of the screw bolt 10 regulates the quantity of gas flowing to the burner 8 and thereby the size of the flame. If said flame should flow back in the gas channel of the burner, it can hardly be transmitted 70 through the said narrow opening.

What I claim is:—

1. A device of the character described comprising a trap structure having an inlet and an outlet, and a mass of fusible metal 75 particles located in said trap in the path of the gas flowing therethrough, said mass permitting the free flow of gas through the trap, and adapted to fuse and form a seal under the influence of heat or flame.

2. A device of the character described comprising a trap structure having an inlet and an outlet, and a mass of fusible particles located in said trap in the path of the gas flowing therethrough, said mass permitting free flow of gas through the trap, and adapted to fuse and form a seal under the influence of heat or flame.

3. A device of the character described comprising a trap structure having an inlet and an outlet, and a mass of fusible particles located in said trap in the path of the gas flowing therethrough, said mass permitting free flow of gas through the trap, and adapted to fuse and form a seal under the 90 influence of heat or flame, said trap being provided with removable bottom whereby the fused mass may be removed.

4. A device of the character described comprising a casing having an inlet and an 100 outlet, a partition within said casing between said inlet and outlet and extending downwardly from the top thereof, the lower edge of said partition being spaced from the bottom of the casing to form a passage, and a mass of fusible particles positioned within said casing and filling said passage 105 whereby the gas must pass through said mass.

5. A device of the character described 110

comprising a casing having an inlet and an outlet, a partition within said casing between said inlet and outlet and extending downwardly from the top thereof, the lower 5 edge of said partition being spaced from the bottom of the casing to form a passage, and a mass of fusible particles positioned within said casing and filling said passage whereby the gas must pass through said 10 mass, said casing being provided with a removable bottom whereby the fused mass may be removed.

6. A device of the character described, comprising a trap structure having an inlet 15 and an outlet with a communicating passage therebetween, and a mass of segregated particles of fusible material located in said communicating passage, said particles normally permitting free flow of gas through 20 the trap, but adapted to fuse under the influence of heat and close said passage.

7. A device of the character described, comprising an apparatus for mixing gas and air, an incandescent burner, a conduit 25 connecting the mixing apparatus with the burner for conducting the mixture under pressure to the latter, means arranged within the conduit adjacent to the burner for restricting the size of the passageway to

resist back flow of the flame, and a thermostatic device provided within the conduit adjacent to the mixing apparatus and adapted to be actuated by a back flow of flame to seal the conduit. 30

8. A device of the character described, comprising an apparatus for mixing gas and air, an incandescent burner, a conduit leading from the mixing apparatus to the burner for conducting mixture to the latter, the said conduit being closed from the external air throughout its entire length, and two means provided within the conduit in 35 succession for preventing a back flow of flame from the burner to the mixing apparatus, one of the said means comprising a restricted passage arranged in proximity to the burner, and the other means being arranged adjacent to the mixing apparatus and containing a fusible mass adapted to fuse under the influence of the flame to seal 40 the conduit at this part. 45

In testimony whereof I have signed my name to this specification in the presence of two subscribing witnesses.

GUSTAF DALEN.
